CLAIM

The ornamental design for a gas hose with gauge, as shown and described.

DESCRIPTION

FIG. 1 is perspective front view of the gas hose with gauge;
FIG. 2 is a first side view thereof;
FIG. 3 is a second side view thereof;
FIG. 4 is a first end view thereof;
FIG. 5 is a second end view thereof;
FIG. 6 is a top view thereof; and,
FIG. 7 is a bottom view thereof.

The broken lines in the drawings form no part of the claimed design.
